United States Patent Office

Des. 181,613
Patented Dec. 3, 1957

181,613

BRUSH DISPLAY UNIT

Harold Swanson, Riverdale, N. Y., assignor to Baker
Brush Co. Inc., New York, N. Y., a corporation of
New York

Application December 17, 1954, Serial No. 33,600

Term of patent 3½ years

(Cl. D80—9)

Fig. 1.

Fig. 2.

Fig. 3.

Fig. 4.

Fig. 5.

Figure 1 is a perspective view of a brush display unit showing my new design;

Fig. 2 is a front elevation view thereof;

Figure 3 is a left end elevational view of Figure 2;

Figure 4 is a right end elevational view of Figure 2; and

Figure 5 is a rear elevational view of Figure 2.

I claim:

The ornamental design for a brush display unit, substantially as shown.
